UNITED STATES PATENT OFFICE.

LESLIE J. BANKS, OF EAST NORWALK, CONNECTICUT.

LID SUPPORT.

Application filed April 12, 1922. Serial No. 551,901.

To all whom it may concern:

Be it known that I, LESLIE J. BANKS, a citizen of the United States, residing at East Norwalk, in the county of Fairfield and 5 State of Connecticut, have invented certain new and useful Improvements in Lid Supports, of which the following is a specification.

My invention relates to improvements in 10 lid supports and has for its main object to provide an automatic guide for the support, operating to conduct the latter during the opening or closing of the lid of a cabinet, chest, box, or the like, provided with a 15 hinged lid.

Another object of the present invention is to provide a support or stay that will hold 20 the lid firmly in open position, but which requires only a slight additional raising of 25 the lid from said position to operate the guide and permit the closing of the lid.

In the accompanying drawing one embodiment of the invention is illustrated, and

Figure 1 shows a fragmentary elevation 25 and part section of a cabinet with its lid open;

Fig. 2 is a perspective view of the details constituting part of the invention;

Fig. 3 is a side elevation of the device with 30 the lid partly open, and

Fig. 4 is a similar view showing the position of the device with the lid partly closed.

In the drawing reference numeral 10 represents the top part of the box or cabinet 35 with a lid 11 hinged, as at 12. A stay-rod 13 preferably made of flat metallic band, is pivoted, as at 14, on a bracket 15 secured by means of screws, rivets or the like on the inside of the lid. At the free end of the 40 stay-rod 13 is rigidly secured a stud 16 pointing outwardly as regards the cabinet and the stay-rod 13 runs through a plate 17 provided with a longitudinal slot 18 for this purpose. This plate is secured by means of screws or 45 rivets, as at 19, on the top edge of the side wall in the cabinet. The slot 18 is slightly wider than the thickness of the stay-rod 13 and the plate 17 forms a stop for the stud 16 on the rod to limit the upward motion 50 of the lid 11.

On the underside of the plate 17 is rigidly secured, or forming a part thereof, a bearing 20, which hangs down perpendicularly in a recess 21 provided in the side of the cabinet, 55 in such a manner, that the bearing is concealed both from the inside and the outside

of the cabinet. This bearing 20 has a jaw portion 22 which is notched, as at 23, to provide a seat for the stud 16 on the guide rod 13, when the lid is open and in 60 this manner supporting the weight of the lid at the bottom of the notch. The jaw 22 does not reach all the way up to the plate 17, but is spaced therefrom so as to provide an entrance and exit for the stud 16 to and from 65 the notch 23. The jaw 22 has a circular upper front edge and a pivot pin 24 is located centrally as regards this edge. This pivot pin projects on both sides of the bearing 20 and the inner end thereof forms a guide 70 upon which the lower edge of the stay-rod 13 rides during the opening or closing of the lid. The relative position of the parts is such that the outer side of the stay-rod 13 lies flat against the inner side of the bearing 75 20, while the stud 16 projects across the front edge 25 of the jaw 22 on the bearing.

Upon the outwardly directed end of the pivot pin 24 is hung a dog 26 having a comparatively short head portion 27 and a reinforced lower portion 28 for the purpose of suspending the dog 26 in approximately 80 perpendicular direction from the pivot pin 24. The dog is preferably made out of thin sheet metal and lies flat against the outer 85 side of the bearing 20 and is able to swing easily upon the pin when actuated by the stud 16 at the lower end of the stay-rod 13. The head 27 of the dog has a forwardly projecting nose 29 from which a lip 30 extends 90 sideways and outwardly from the dog in such a manner that the lip is situated in the path of the stud 16 when the latter is travelling in upward direction. In this lip is formed a channel 31 slightly wider than the 95 diameter of the stud 16 providing a passage for the stud, when the lid is going to be closed.

The operation of the device is as follows: 100 When the lid is going to be raised, the forward side thereof is lifted bringing the stay-rod 13 with it when the lower edge 32 of the latter will slide upon the pivot pin 24, as seen in Fig. 3. While the lid is closed and during the opening operation the dog 105 26 takes the upright position shown in Fig. 3, that is to say, the lip 30 stands out over the circular edge 25 of the jaw 22. When subsequently the stud 16 contacts with the lip 30 the latter swings concentrically with 110 the edge 25 around its pivot 24, while the stud 16 follows the edge 25 until it arrives

above the notch 23 pushing the lip 30 with it. The lip 30 and the stud 16 remain in contact during this time and when the stud 16 finally strikes the underside of the plate 17 at the right angular corner 33 formed therewith by the bearing 20, the lid can be raised no further and when released it will move slightly downwards until the stud 16 rests in the bottom of the notch 23. The 10 lid is now held in open position, as best seen in Fig. 1, with the head 27 of the dog 26 held back by the stud, as indicated in dotted lines.

In order to again close the lid the latter is 15 slightly raised, when the stud 16 will again move upward until it strikes the bottom face of the plate 17, as indicated by dotted lines in Fig. 4, but at this time it will pass through the channel 31 which is partly open 20 to the rear, as at 34, thereby permitting the dog to swing into its upright position. As the radius of the curvature of the head 27 forming an arched top 35 is greater than the radius of the edge 25 of the jaw 22, this 25 top 35 will now guide the stud 16 out of the notch 23, while the dog 26 is tilted forward, as seen in Fig. 4, so that the stay-rod 13 will be free to pass downwardly and the lid can be closed.

30 Having thus described the invention, what is claimed as new is:

1. A lid support for a cabinet comprising a stay-rod, pivotally suspended from said lid, a stud on said stay-rod, a bearing 35 on the cabinet for said stud provided with an open jaw and with a circular front face, a pivot centrally located as regards said circular face, said pivot adapted to conduct said stud into engagement with said circular

face and the latter adapted subsequently to 40 guide said stud into said jaw during the opening action of said lid.

2. A lid support for a cabinet comprising a stay-rod, pivotally suspended from said lid, a stud on said stay-rod, a bearing on the 45 cabinet for said stud provided with an open jaw and with a circular front face, a pivot centrally located as regards said circular face, a dog suspended from said pivot, and provided with an arcuate head of greater 50 radius than said front face, a lip on the head situated in the upward path of said stud, said lip having a rearwardly open channel adapted to conduct said stud out of 55 said jaw into engagement with said arcuate head during the closing operation of the lid.

3. A lid support for a cabinet comprising a stay-rod pivotally suspended from said lid, a stud on said stay-rod, a bearing on the cabinet for said stud provided with an 60 open jaw and with a circular front face, a pivot centrally located as regards said circular face, a dog suspended from said pivot and provided with an arcuate head of greater radius than said front face, a lip on 65 the head situated in the upward path of said stud, said lip having a rearwardly open channel adapted to conduct said stud out of 70 said jaw into engagement with said arcuate head during the closing operation of the lid. 75

In testimony whereof I affix my signature.

LESLIE J. BANKS. [L.S.]
